UNITED STATES PATENT OFFICE.

JOHN CLEMENT, OF BIRMINGHAM, ENGLAND.

DESIGN FOR AN OIL-CAN.

SPECIFICATION forming part of Design No. 25,395, dated April 14, 1896.

Application filed January 2, 1896. Serial No. 574,149. Term of patent 7 years.

To all whom it may concern:

Be it known that I, JOHN CLEMENT, a subject of Her Majesty the Queen of Great Britain and Ireland, residing at Birmingham, in the county of Warwick, England, have invented a new and original Design for Oil-Cans, of which the following is a specification.

Figure 1 is a front, and Fig. 2 a side, view of my design. The features of my design consist in the oval shape of the body as viewed from the side in Fig. 1, the edge of the body being a continuous curve extending to and merging into the curved bottom edge and the substantially

flat sides as viewed in Fig. 2, these sides being slightly convexed from the top to the bottom and meeting in sharp side and bottom edges.

I claim—

The design for an oil-can herein shown and described.

In witness whereof I have hereunto set my hand in presence of two witnesses.

JOHN CLEMENT.
